UNITED STATES PATENT OFFICE.

WILLIAM J. FITZGERALD, OF NEW HAVEN, CONNECTICUT, ASSIGNOR TO
HOBERT B. IVES, OF SAME PLACE.

CIGAR-HOLDER.

SPECIFICATION forming part of Letters Patent No. 252,753, dated January 24, 1882.

Application filed July 22, 1881. (No model.)

To all whom it may concern:

Be it known that I, WILLIAM J. FITZGERALD, a citizen of the United States of America, residing at New Haven, in the county of New Haven and State of Connecticut, have invented certain new and useful Improvements in Cigar or Cigarette Holders; and I do hereby declare the following is a full, clear, and exact description of the invention, such as will enable others skilled in the art to which it appertains to make and use the same, reference being had to the accompanying drawings, and to letters or figures of reference marked thereon, which form a part of this specification, and in which—

15 Figure 1 is perspective view of my improved cigar and cigarette holder, and Fig. 2 is a view in elevation thereof with the movement of the jaws indicated in dotted lines.

This invention has relation to improvements 20 in devices adapted to hold cigars and cigarettes, and is characteristic for the facility with which it can be adjusted to and removed from the cigarette or cigar and the security of its grasp thereon; and it consists of parallel spring-plates 25 provided at one end with jaws adapted to clasp a cigar and at the other end with jaws to clasp a cigarette, while between the uniting points or points of contact they are provided with compressible springs, substantially as herein- 30 after more fully set forth and claimed.

In carrying out my invention I employ, as will be clearly seen by reference to the accompanying drawings, two spring-metal plates, A A, arranged parallel and having two uniting 35 points, as at a a, one near each jaw, presently described. The plates are capable of a springing motion upon the uniting-rivets a, as will be more fully seen hereinafter.

At one of the ends of each of the plates A there is provided a segmental jaw, B, which jaws meet 40 at their outer ends, and are adapted to receive and clasp a cigar, while the other ends of the plates are provided with similar but smaller jaws, B' B', to enable them to receive and clasp a cigarette. Between their uniting points or 45 rivets a the plates are each provided with a semi-elliptical or outwardly-curved portion, C, the action of which, it will be seen, when compressed is to cause the outer meeting ends of the jaws to separate, and thus permit of the 50 insertion of the cigarette or cigar, or the slipping of the jaws upon the cigar or cigarette sufficiently far as that, when pressure is removed from the spring C, the jaws will clasp and secure the inserted cigar or cigarette. The 55 operation for removing the cigar or cigarette is obviously by again compressing the springs, which will permit it to fall out.

From the foregoing it will be readily understood how this device serves to enable the holding of the cigarette or cigar while smoking.

Having thus fully described my invention, I claim and desire to secure by Letters Patent—

The cigar or cigarette holder consisting of the parallel spring-plates A, having each a 65 curved meeting jaw, B, and provided with a compressible spring, C, between their uniting rivets or points a, substantially as and for the purpose set forth.

In testimony whereof I affix my signature in 70 presence of two witnesses.

WILLIAM J. FITZGERALD.
